UNITED STATES PATENT OFFICE.

MERTON D. PHELAN, OF LYNN, MASSACHUSETTS, ASSIGNOR TO UNITED SHOE MACHINERY CORPORATION, OF PATERSON, NEW JERSEY, A CORPORATION OF NEW JERSEY.

NAIL-MAKING MACHINE.

Application filed February 21, 1921. Serial No. 446,656.

This invention relates to strip feeding mechanism and is herein illustrated and described as embodied in a nail making machine in which the nails are cut from blanks 5 successively fed to the cutting dies thereof.

An application for Letters Patent, Serial No. 169,562, filed May 18, 1917, by George Goddu, for blank feeding mechanism, which has issued as Patent No. 1,396,191, granted 10 Nov. 8, 1921, discloses mechanism for feeding strips to a nail making machine comprising a carrier for presenting the strips to the machine and means controlled by a strip in the carrier for automatically supplying 15 strips to the carrier. One of the objects of the present invention is to provide improved and simplified mechanism of the same general character as that forming the subject-matter of that application.

With this and other objects in view, a feature of the invention comprises novel means for feeding a nail strip towards nail severing position either with or without mechanism rendered operative by the passing 25 of the strip out of contact with a suitably arranged feeler to supply a new blank to the feeding means.

Another feature of the invention comprises a novel combination comprising a feed dog normally out of gripping engagement with the nail blank and means for moving the feed dog into and out of gripping relation to the blank at the commencement and conclusion respectively of each 35 feeding movement thereof. In the illustrated machine this feed dog is mounted upon a rotary carrier and is provided with a cam portion arranged, as the carrier rotates, to be wiped by a cam roll, first to move the dog into gripping engagement with the nail strip and then to oscillate the lever to feed the nail strip a step forward toward the cutting dies. At the conclusion of the feeding movement the cam of the feed dog passes from the roll and the dog is moved 40 back out of gripping relation to the nail strip for the return movement of the oscillating lever.

A further feature of the invention consists of simplified mechanism by which the passage of a nail strip from an appropriate

part of the feeding mechanism is utilized to initiate the operation of a transfer device to supply a fresh strip to the feeding mechanism. With this in view, the illustrated machine is provided with a feeler and a control finger adjacent thereto, these parts being so positioned that they normally contact with the opposite sides of a nail strip which passes between them. The end of the feeler remote from the nail strip is arranged to pass by without moving a pair of wipers as long as a nail strip lies between the feeler and the control finger. When, however, the nail strip passes from that position the feeler rocks about its pivot, swinging the end thereof into such position that it is operative to rock the first wiper into position to cause the throwing in of a clutch which controls the transfer device and thus initiates supply of a fresh nail strip to the feeding means. Further movement of the feeler brings it into engagement with the second wiper which results in moving the point of the feeler around the end of the control finger to the other side thereof against the action of a spring which normally holds it in contact with the nail strip. In this position it is held by the control finger so that its path of movement is such that it can pass by the first wiper during continued operation of the machine without movement thereof. The same movement of the second wiper which thus operates to shift the feeler is utilized to throw, or to insure the throwing of, the clutch into inoperative condition to prevent the continuous repeated operation of the transfer device or, indeed, any operation thereof subsequent to the first until after the 50 feeler has been moved to its normal, nail strip engaging position by the supplying of a fresh nail strip to the feeding mechanism.

With these and other objects and features in view the invention will now be described in connection with the accompanying drawings, which show an illustrative embodiment thereof, and pointed out in the appended claims.

In the drawings,

Fig. 1 is a side elevation of a machine embodying this invention;

Fig. 2 is a plan view of the strip feeding mechanism showing also a portion of

the magazine from which the strips are supplied;

Fig. 3 is a perspective view, partly broken away better to disclose the construction of the strip feeding mechanism;

Figs. 4 and 5 are similar side elevations partly broken away and showing two different positions of the feeler and its associated parts;

10 Fig. 6 is an elevational view of the adjacent ends of the feeler, control finger and feed dogs showing their position immediately after the passing of a strip from the feeding mechanism;

15 Fig. 7 is an exploded view of a clutch which may be utilized to operate the magazine and transfer mechanism.

The illustrated machine is provided with a frame 2 upon which is mounted a head 4 carrying mechanism for operating upon a nail strip which, as shown, includes cutting dies 6 reciprocated by a cam shaft 8 past the edge of a stationary anvil 10. The nail strip is presented to the cutting dies by a rotary carrier 12, the main casting 14 of which is fulcrumed at 16 to a yoke 18 upstanding from a frame 20, this frame being preferably attached to the frame 2 in such manner that it is universally adjustable about the 25 cutting dies as a center. The carrier 12 is shown as provided with tight and loose sprockets 22 and 24, the former being rotated by a chain 26 driven from the shaft 28 rendered flexible by universal joints 30 or 30 other suitable means to permit adjustment of the frame 20 without cramping that shaft. The shaft 28 is driven from the cam shaft 8 by suitable gearing including a pair of elliptical gears 32 so arranged as to cause 35 the velocity of rotation of the carrier 12 to be at a minimum when the strip is horizontal and the cutting dies are operating to sever a nail therefrom and to be at a maximum when the strip is vertical in its movement from one nail severing position to the 40 next.

Gears 22 and 24 are connected by a clutch mechanism illustrated in Fig. 7 and consisting of two main clutch members rigidly carried by sprockets 22 and 24 respectively and a pawl 34 arranged, when in one position, to connect the clutch members so as to render the clutch operative, and when in another position, to disconnect the clutch members so that the clutch shall be inoperative to cause movement of the parts driven therefrom. When this pawl 34 is in the position indicated in Fig. 3 the clutch members are disconnected but when the pawl is permitted to drop from that position it becomes operative to connect the two parts of the clutch so that the gear 24 is positively rotated. Passing over sprocket 24 is a chain 36 which, when driven, is operative through suitable mechanism to rotate the magazine, as by a

Geneva gear 38, and to oscillate a lever 40 connected by a link 42 with a transfer member 44 slidably carried upon a rod 46. Oscillation of the lever 40 from the position shown in Fig. 1 to the right and back again results in transferring a nail strip from the magazine to the carrier 12.

The structure so far described is not claimed to be novel with applicant, being substantially that set forth in the United States Letters Patent No. 1,396,191, granted on the application of George Goddu hereinbefore referred to, to which patent reference may be had for a fuller description thereof.

The rotary carrier 12 includes a frame 50 journaled in suitable bearings 52 and is provided with a passage 54 (Fig. 3), through which nail strips 56 may be successively passed. Fulcrumed at 58 upon the carrier 50 is a lever 60 normally held towards the right, as viewed in Figs. 4 and 5, by a spring 62. Mounted upon lever 60 is a fixed feed dog 64 and pivotally carried by that lever is a movable feed dog 66 provided with a spring 68 tending to hold it away from the nail strip and against a stop 70. The end of this dog remote from the nail strip is formed as a cam 72 (see Fig. 3) arranged, as the carrier is rotated, for wiping contact with rolls 74, 76 adjustably carried by a yoke 77 mounted upon the casting 14. Thus dog 66 is moved into gripping engagement with the nail strip and lever 60 and the two dogs are oscillated to feed the nail strip to the nail making machine. The end of the lever 60 is shaped, as shown at 78, to form a continuation of cam 72 to insure the easy return of the lever after each feeding movement thereof.

From the foregoing, it will be clear that as the carrier 12 rotates the cam end 72 of feed dog 66 will repeatedly wipe the rolls 74 and 76 and that at each such impact that dog will be moved into gripping engagement with the nail strip which will thus be pinched between the two dogs and will be held so pinched during its feeding movement. At the conclusion of each feeding movement thus produced the cam end of dog 66 will pass from the roll 74 or 76 and, as cam 78 passes by the roll, lever 60 will be returned by spring 62 to its normal position, dog 66 at this time being held out of gripping engagement with the nail strip by its spring 68.

To accomplish the transfer of successive nail strips from the magazine to the feeding device a feeler 80 is provided, pivoted at 82 to the frame 50 of the carrier, a compression spring 84 being operative normally to hold the feeler in engagement with the nail strip. The end 86 of the feeler remote from the nail strip is positioned normally to pass by without moving a pair of wipers 88 and 90 (Fig. 3) rigidly mounted upon one end

of a rock shaft 92, the other end of which carries a dog 94 normally interposed in the path of movement of pawl 34 to prevent the operation of the clutch 33. A torsion spring 96 tends to move dog 94 into the position indicated in Fig. 3, its further movement towards the clutch being prevented by stops 98.

Adjacent to the feeler 80 and normally, as shown in Figs. 3 and 4, on the opposite side of the nail strip therefrom is a control finger 100 pivoted at 102 to the frame 50 and provided with a spring 104 tending to move it in a counter clockwise direction, as viewed in Fig. 4 against a stop 106.

Upon the passage of a nail strip out of engagement with the end of the feeler 80, the feeler under the influence of the spring 84 assumes the position shown in Fig. 6. In this position its end 86 during the rotation of the carrier presently engages wiper 88, rocking it and the dog 94 in a clockwise direction, as viewed in Fig. 3 and thus removing dog 94 from the position shown in that figure in which it restrains pawl 34. The clutch is thus rendered operative to move the transfer member 44 to the right as viewed in Fig. 1, to rotate the magazine a step, and then to move the transfer member 44 back to push a nail strip from the magazine into the carrier 12. The shape and location of feeler 80 is such that the incoming end of the nail strip forces it from the position of Fig. 6 back to that of Fig. 4 and the feeding operation continues in its normal fashion until that nail strip passes beyond the feeler.

If, for any reason, such as an empty magazine or a jam caused by a misshapen nail strip, the transfer device fails to supply a fresh nail strip to the carrier, it is desirable that further operation of the transfer device be prevented. Accordingly, the wiper 90 is utilized to throw dog 94 positively back into operative position, if for any reason spring 96 fails to act, so that it will catch pawl 34 at the completion of a single rotation thereof, wiper 90 also being operative to rotate the feeler 80 through a small angle in a counter clockwise direction, as viewed in Fig. 5, to such an extent that the end thereof adjacent to the nail strip moves to the left of the controlling finger 100, as viewed in Figs. 4 and 5, until it assumes the position of Fig. 5. In this position it is held by the control finger 100 with its end 86 in such position that, during further rotation of the carrier, it passes by wiper 88 without engagement therewith. Continued, repeated operation of the transfer device is thus prevented. At the same time, the parts are in such condition that, upon the supplying of another nail strip to the feeding mechanism, the fresh nail strip may pass between the ends of feeler 80 and the control finger 100 so as to force those members into their usual posi-

tion and to permit the nail strip to be fed by the feed dog in the normal manner.

Having described my invention, what I claim as new and desire to secure by Letters Patent of the United States is:—

1. A nail making machine having, in combination, cutting dies for severing nails from nail strips, a carrier for presenting the nail strips to the cutting dies, a feed dog mounted upon the carrier and arranged for movement to grip and feed a nail strip step by step toward the cutting dies, said feed dog being normally out of gripping engagement with the nail strip being fed, a magazine constructed to hold a plurality of the nail strips, and a transfer device to feed the nail strips successively from the magazine to the carrier.

2. In a machine of the class described, the combination of means for operating upon an elongated blank, a carrier for presenting the blank to the operating means, and a lever fulcrumed upon the carrier and provided with a pair of blank feeding dogs arranged, upon oscillation of the lever, to engage and to feed the blank to the operating means, said feeding dogs being normally out of gripping engagement with the blank being fed.

3. A machine of the class described having, in combination, means for operating upon elongated blanks, a rotary carrier for presenting blanks to the operating means, a lever fulcrumed upon the carrier and provided with a pair of blank feeding dogs operable upon oscillation of the lever to feed a blank step by step to the operating means, and a member arranged in the path of movement of the lever to oscillate the lever as the carrier rotates.

4. A machine of the class described having, in combination, means for operating upon elongated blanks, a rotary carrier for presenting blanks to the operating means, a cam bearing lever fulcrumed upon the carrier and provided with a pair of blank feeding dogs operable upon oscillation of the lever to feed a blank step by step to the operating means, and a roll arranged in the path of movement of the cam of said lever to oscillate the lever as the carrier rotates.

5. In a machine of the class described, the combination of means for operating upon elongated blanks, a rotary carrier for presenting blanks to the operating means, and a lever fulcrumed upon the rotary carrier and provided with a pair of blank feeding dogs arranged, upon oscillation of the lever, to feed the blanks to the operating means.

6. A machine of the class described having, in combination, means for operating upon elongated blanks, a carrier for presenting a blank to the operating means, a lever fulcrumed upon the carrier and provided with a pair of feed dogs arranged to feed

- the blank step by step to the operating means as the lever is oscillated, and means periodically to oscillate the lever.
7. A machine of the class described having, in combination, means for operating upon elongated blanks, a rotary carrier for presenting a blank to the operating means, a lever fulcrumed upon the carrier and provided with a pair of feed dogs arranged to feed the blank step by step to the operating means as the lever is oscillated, and means to oscillate the lever once for each semi-rotation of the carrier.
8. A machine of the class described having, in combination, means for operating upon elongated blanks, a carrier for presenting the blanks to the operating means, a relatively fixed feed dog, a pivoted feed dog, and means for shifting the pivoted feed dog into engagement with a blank to grip the blank between the dogs during the feeding movement and to permit the release of the blank between feeding movements.
9. A machine of the class described having, in combination, means for operating upon elongated blanks, a rotary carrier for presenting the blanks to the operating means, a lever fulcrumed upon the carrier, a feed dog fixedly carried by the lever, a second feed dog movably carried by the lever, and means for oscillating the lever arranged to shift the movable feed dog into engagement with a blank to grip the blank between the dogs during the feeding movement of the lever and to permit the release of the movable dog from gripping engagement with the blank during the return movement of the lever.
10. A machine of the class described having, in combination, means for operating upon elongated blanks, a rotary carrier arranged to present blanks to the operating means, a cam bearing lever fulcrumed on said carrier, a pair of blank feeding dogs carried by said lever, and a member mounted in the path of movement of said lever for wiping engagement with the cam thereof to oscillate the lever during the rotation of the carrier.
11. A machine of the class described having, in combination, means for operating upon elongated blanks, a rotary carrier for presenting blanks to the operating means, a lever fulcrumed on said carrier, a pair of feed dogs carried by said lever and arranged to feed the blank a step towards the operating means upon each oscillation of said lever, and cam means arranged to oscillate said lever as the carrier rotates.
12. A machine of the class described having, in combination, means for operating upon elongated blanks, a rotary carrier for presenting blanks to the operating means, a lever carried by the carrier and itself carrying a pair of blank engaging dogs arranged upon oscillation of the lever to feed a blank step by step to the operating means, and cam mechanism arranged to oscillate said lever during the rotation of the carrier by a wiping action to cause the dogs to grip the blank during their feeding movement and to release the blank during their return movement.
13. A machine of the class described having, in combination, means for operating upon elongated blanks, a rotary carrier arranged to present blanks to the operating means, a lever fulcrumed on said carrier, a pair of blank feeding dogs carried by said lever, a cam carried by one of said dogs, and a roll mounted in the path of movement of said cam for wiping engagement therewith to oscillate the lever during the rotation of the carrier.
14. A machine of the class described having, in combination, means for operating upon elongated blanks, a rotary carrier for presenting blanks to the operating means, a lever fulcrumed on said carrier, a pair of feed dogs carried by said lever and arranged to feed the blank a step towards the operating means upon each oscillation of said lever, a cam carried by one of said dogs and means arranged for wiping contact with said cam to oscillate said lever as the carrier rotates.
15. A machine of the class described having, in combination, means for operating upon elongated blanks, a carrier for feeding blanks thereto, a lever fulcrumed upon the carrier, a feed dog fixedly mounted upon the lever, a second feed dog pivoted to the lever, yielding means tending to hold the movable dog out of engagement with a blank in the carrier, and means arranged in the path of movement of the lever for oscillating the lever and for shifting the movable dog into gripping engagement with the blank during the feeding movement thereof to feed the blanks step by step toward the operating means.
16. A machine of the class described having, in combination, means for operating upon blanks, a relatively fixed feed dog and a pivoted feed dog, yielding means tending to hold the pivoted dog out of engagement with a blank to be fed, and means for shifting the pivoted dog into gripping engagement with the blank and for moving the dogs to feed the blank toward the operating means while so gripped.
17. Strip feeding mechanism having, in combination, a rotary carrier, a lever carried thereby, a member arranged in the path of movement of said lever to have a wiping action thereon to oscillate the lever as the carrier rotates, and a feed member carried by the lever and directly engaging a blank to feed the blank during the oscillation of the lever.

18. Strip feeding mechanism having, in combination, a rotary carrier, a lever carried thereby, a member arranged in the path of movement of said lever to have a wiping action thereon during the rotation of said carrier to oscillate the lever, and a pair of feed dogs carried by the lever and operable to grip and feed a blank during the movement of the lever in one direction and to be released from gripping engagement with the blank during movement of the lever in the other direction.

19. Strip feeding mechanism having, in combination, a rotary carrier, a lever fulcrumed to said carrier, a feed dog pivoted to the lever, means tending to move said dog out of gripping engagement with a blank to be fed through the carrier and a member arranged in the path of movement of a part of said movable dog for engagement therewith to oscillate said lever and to move said dog into gripping engagement with the blank during the feeding movement thereof.

20. Strip feeding mechanism having, in combination, a rotary carrier, a lever fulcrumed to said carrier, a feed dog pivoted to the lever, a spring tending to move said dog out of gripping engagement with a blank to be fed through the carrier and a member arranged in the path of movement of a part of said movable dog for wiping engagement therewith to oscillate said lever and to move said dog into gripping engagement with the blank during the feeding movement of the lever and to permit the release of said dog from gripping engagement with the blank during the return movement of the lever.

21. A machine of the class described having, in combination, a carrier for blanks, an oscillating lever fulcrumed directly upon said carrier, a feed dog fixed to said lever, a feeler arranged normally to contact with a blank in the carrier and displaceable upon the passage of a blank out of contact therewith, and mechanism controlled by said feeler for supplying a new blank to the carrier upon such displacement of the feeler.

22. A machine of the class described having, in combination, means for operating upon elongated blanks, a carrier for presenting blanks to the operating means, an oscillatable lever fulcrumed upon said carrier, a blank-engaging feed dog fixed to said lever, a feeler arranged normally to contact with a blank in the carrier and displaceable upon the passage of a blank out of contact therewith, and mechanism controlled by said feeler for supplying a new blank to the carrier upon such displacement of the feeler.

23. A machine of the class described having, in combination, blank feeding mechanism, a feeler arranged normally to contact with a blank in said mechanism and displaced upon movement of the blank out of contact therewith, a clutch, a transfer de-

vice operated by said clutch to supply blanks to the feeding mechanism, a dog arranged normally to hold said clutch in inoperative condition, and a wiper rigidly connected to said dog and positioned in the path of movement of a portion of said feeler when in its displaced condition for movement thereby to cause the withdrawal of said clutch controlling dog.

24. A machine of the class described having, in combination, means for operating upon blanks, a carrier for presenting blanks thereto, a feeler arranged normally for contact with a blank in said carrier and displaced by the movement of a blank out of contact therewith, means for supplying blanks to said carrier controlled by the position of said feeler, and means arranged to hold said feeler in position to prevent further operation of the blank supplying means after a single operation thereof, irrespective of whether a blank has or has not been supplied by said single operation.

25. A machine of the class described having, in combination, means for operating upon blanks, a carrier for presenting blanks thereto, a feeler arranged normally for contact with a blank in said carrier and displaced by the movement of a blank out of contact therewith, a transfer device for supplying blanks to said carrier controlled by the position of said feeler, and a finger arranged to hold said feeler in position to prevent the supplying of blanks by the transfer device after a single operation, irrespective of whether a blank has or has not been supplied by said single operation.

26. Blank feeding mechanism including a feeler arranged to contact with a blank and displaced upon passage of a blank out of contact therewith, means, the operation of which is initiated by such displacement of the feeler, to supply a blank to the feeding means, and means arranged to move said feeler out of said supply initiating position after a single operation of said blank supplying means.

27. The combination of blank feeding mechanism, a feeler arranged normally to contact with a blank therein and displaced upon movement of the blank out of contact therewith, a control finger adjacent to said feeler, means for supplying blanks to said carrier operable upon displacement of said feeler, and means to change the position of said feeler and said control finger relatively to each other to render said feeler inoperative to cause a subsequent operation of the supply means if the first operation thereof is ineffectual to supply a blank to the carrier.

28. Blank feeding mechanism including a feeler arranged to contact with a blank and displaced upon passage of a blank out of contact therewith, means, the operation of which is initiated by such displacement of

said feeler, to supply a blank to the feeding means, and a wiper arranged to move said feeler out of said supply initiating movement after a single operation of said blank supplying means.

29. Blank feeding mechanism having, in combination, a feeler arranged normally to contact with a blank in said mechanism and displaced upon movement of a blank out of contact therewith, means for supplying blanks to said carrier, a pair of wipers arranged for engagement with a portion of said feeler when in its displaced condition, first to initiate the operation of said blank supplying means and second to restrain operation thereof after a single blank supplying movement, the second wiper being arranged to move said portion of the feeler so that the first wiper will no longer engage therewith.

30. Blank feeding mechanism having, in combination, a blank carrier, means for feeding blanks thereto, a feeler arranged normally to contact with a blank in said carrier and displaced upon movement of a blank out of contact therewith, means for supplying blanks to said carrier, a pair of wipers arranged in the path of movement of a portion of said feeler when in its displaced condition, first to initiate the operation of said blank supplying means and second to restrain operation thereof after a single blank supplying movement, the second wiper being arranged to move said portion of the feeler so that the first wiper is no longer in the path thereof.

31. Blank feeding mechanism having, in combination, a feeler arranged normally to contact with a blank therein and displaced upon passage of a blank out of contact therewith, a transfer device operable to supply a blank to the feeding mechanism upon such displacement of said feeler, and means to move said feeler to a position to restrain subsequent operation of said transfer device after the first operation of the transfer device regardless of whether a blank is actually supplied.

32. Blank feeding mechanism having a feeler and a control finger arranged for the passage of a blank therebetween, said feeler being displaced relatively to said control finger by the passage of a blank out of contact therewith, means rendered operative by the displacement of said feeler to supply another blank to the feeding mechanism, and means operable after the relative displacement of said feeler and said control finger further relatively to move said feeler and said control finger upon the continued absence of a blank therefrom whereby the blank-supplying means is rendered inoperative.

33. Blank feeding mechanism having, in

combination, a feeler and a control finger arranged for the passage of a blank therebetween, said feeler being displaced to one side of said control finger by the passage of a blank out of contact therewith, means rendered operative by the displacement of said feeler to supply another blank to the feeding mechanism, and means operable after the displacement of said feeler; to move said feeler to the other side of said control finger upon the continued absence of a blank therefrom whereby the blank-supplying means is rendered inoperative.

34. Blank feeding mechanism having, in combination, a carrier arranged for the passage of a blank therethrough, a feeler and a control finger arranged for passage of a blank in the carrier therebetween, yielding means for displacing said finger upon passage of a blank out of contact therewith, a transfer device operable upon displacement of said finger to supply a new blank to the carrier, and means relatively to move said feeler and said control finger so as to cause the latter to hold the former out of the position in which it causes operation of said transfer device to prevent continuous, repeated operation thereof.

35. Blank feeding mechanism having, in combination, a feeler arranged for displacement upon the passage of a blank out of contact therewith, a clutch arranged to control the supply of blanks to the feeding mechanism, a dog arranged normally to restrain the clutch in inoperative condition, and a pair of wipers rigidly connected to the dog and arranged in the path of movement of a portion of the feeler when in such displaced condition first to move the dog out of clutch restraining position and subsequently to prevent movement of the dog out of clutch restraining position until after the supply of a fresh blank to the feeding mechanism.

36. Blank feeding mechanism having, in combination, a feeler arranged normally to contact with a blank in said mechanism and displaceable upon passage of a blank out of contact therewith, a rock-shaft, a clutch controlling dog carried thereby, and a pair of wipers rigidly connected to said rock-shaft arranged in the path of movement of said feeler when in its displaced position for successive engagement therewith to move the dog out of and subsequently back into clutch restraining position.

37. A nail making machine having, in combination, a movable feeler, a clutch, means operated by said clutch for supplying blanks to the machine, a dog arranged to control the operation of said clutch, a pair of wipers connected to said dog and arranged for engagement with said feeler to move the dog out of and subsequently

back into clutch restraining position to cause the clutch to operate the transfer device to supply strips successively to the feeding mechanism.

5. 38. In a machine for operating on work, a clutch, a clutch controller comprising a clutch controlling dog, a pair of wipers rigidly connected to the dog for causing operation thereof, and means controlled by 10 the work for determining the time of operation of the wipers.

39. In a machine for operating on work, a clutch, a clutch controller comprising a pair of rigidly connected wipers, a clutch 15 controlling dog operatively connected thereto for movement thereby, and means arranged to contact with the work for controlling the operation of said wipers.

40. In a machine for operating on work, 20 a clutch, a clutch controller comprising a clutch controlling dog, a pair of wipers connected thereto to control the operative relation of the dog and the clutch, and a member movable upon exhaustion of the 25 work for controlling the operation of said wipers.

41. In a machine of the class described, 30 the combination of means for operating upon an elongated blank, a carrier for presenting the blank to the operating means, means for moving the carrier relatively to the operating means between successive operations on the blank, a member movably mounted upon the carrier, means operated by the 35 movement of the carrier to move said movably mounted means, and a pair of blank gripping and feeding dogs carried by said movably mounted member arranged, upon movement of the member relatively to the 40 carrier, to grip the blank and to feed the blank to the operating means, said feeding dogs being released from gripping engage-

ment with the blank upon the conclusion of the feeding movement.

42. In a machine of the class described, 45 the combination of means for operating upon an elongated blank, a movable carrier for presenting the blank to the operating means, a member movably mounted on the carrier and provided with a pair of blank 50 feeding dogs arranged, upon movement of the member relatively to the carrier, to grip and feed the blank to the operating means, and means operated by the movement 55 of the carrier periodically to move the member relatively to the carrier.

43. A machine of the class described having, in combination, means for operating upon an elongated blank, a rotary carrier for presenting the blank to the operating means, 60 a member movably mounted on the carrier and provided with a pair of feed dogs arranged to feed the blank step by step to the operating means as the member is moved 65 relatively to the carrier, and means operated by the rotation of the carrier periodically to move said member relatively to the carrier.

44. A machine of the class described having, in combination, means for operating 70 upon an elongated blank, a rotary carrier for presenting the blank to the operating means, a lever movably mounted upon the carrier and provided with a pair of feed dogs arranged to grip and to feed the blank 75 step by step to the operating means as the lever is rocked relatively to the carrier, and means for rocking the lever relatively to the carrier and for returning it to its initial position once during each semi-rotation of 80 the carrier.

In testimony whereof I have signed my name to this specification.

MERTON D. PHELAN.
